UNITED STATES PATENT OFFICE.

NEAL J. McKEON, OF OAKLAND, CALIFORNIA.

DESIGN FOR A MANHOLE-COVER.

56,015.

Specification for Design.

Patented Aug. 10, 1920.

Application filed August 23, 1919. Serial No. 319,500. Term of patent 14 years.

To all whom it may concern:

Be it known that I, NEAL J. McKEON, a citizen of the United States, and a resident of Oakland, county of Alameda, State of California, have invented a new, original, and ornamental Design for a Manhole-Cover, of which the following is a specification, reference being had to the accompanying drawings, forming a part thereof.

Fig. 2 is a side view of my cover.

I claim:

The ornamental design of a manhole cover as shown.

NEAL J. McKEON.
